AUTOMATIC SPARK PLUG CLEANER

Filed Aug. 20, 1945

UNITED STATES PATENT OFFICE

2,397,359

AUTOMATIC SPARK PLUG CLEANER

Charles A. Lezensky, Brooklyn, N. Y.

Application August 20, 1945, Serial No. 611,640

6 Claims. (Cl. 123—198)

My invention relates broadly to internal combustion engines, and more particularly to a fitting, attachable to one of the spark plug apertures of an internal combustion engine for facilitating the cleaning of spark plugs.

One of the objects of my invention is to provide an attachment for the spark plug aperture of an internal combustion engine which will accommodate one or more spark plugs which require cleaning in association with an active spark plug which controls combustion in the cylinder of an internal combustion engine for effecting the cleaning of spark plugs.

Still another object of my invention is to provide a construction of attachment for a spark plug aperture of an internal combustion engine which forms an adaptor for receiving an active spark plug, operative in the ignition circuit of an internal combustion engine in association with spark plugs which have become inactive due to an accumulation of carbon deposits and which require cleaning.

Still another object of my invention is to provide a construction of spark plug cleaner arranged to be secured in a spark plug aperture of an internal combustion engine and operative to carry a multiplicity of spark plugs which have become substantially inactive due to the accumulation of carbon deposits in association with an active spark plug, operative in the ignition circuit of the internal combustion engine for effecting through intense heat and pressure a cleaning operation with respect to the inactive spark plugs.

Other and further objects of my invention reside in a construction of cleaner for a multiple number of substantially inactive spark plugs which is effective during the normal operation of an internal combustion engine for cleaning such substantially inactive spark plugs, as set forth more fully in the specification hereinafter following by reference to the accompanying drawing, in which:

Figure 1 is a side elevational view of a fragmentary portion of an internal combustion engine showing the spark plug cleaner of my invention in position in one of the spark plug apertures of the internal combustion engine for effecting a cleaning operation of a multiplicity of substantially inactive spark plugs during the normal operation of the internal combustion engine; Fig. 2 is a vertical sectional view taken through the housing of a spark plug cleaner constructed according to my invention and showing a normally operating spark plug in position for controlling ignition in the associated internal combustion

cylinder and illustrating a group of substantially inactive spark plugs in position for cleaning; Fig. 3 is a horizontal sectional view taken on line 3—3 of Fig. 2; and Fig. 4 is a vertical sectional view of a modified form of spark plug cleaner embodying my invention.

As a result of the relatively poor and only partially combustible low-grade automobile fuels available during the past few years, spark plugs 10 failures in internal combustion engines have been increasing due to accumulation of carbon deposits on the electrodes of the spark plugs at an increasing rate. Such carbon deposits are due largely to a non-gasified strata of low-grade fuel causing 15 carbonaceous accumulation on the spark plug electrodes to such an extent that such accumulation of carbon remains incandescent between the firing intervals. Such an incandescent mass may cause premature firing and burning of the valves 20 with resulting engine inefficiency and rapid deterioration.

Attempts have heretofore been made to eliminate carbonaceous deposits on spark plug electrodes by burning off such deposits, using oxygen 25 jets, but such efforts have been rather disappointing because such work is necessarily carried on while the spark plug is cold and under sudden rise of temperature, due to the excessive heat of the oxygen flame, such treatment frequently results in the cracking of the porcelain insulators 30 and/or the accompanying crystallization of the metal of the spark plug electrodes. These disadvantages are eliminated by my invention.

The attachment of my invention has been developed 35 as a substitution for a spark plug in the spark plug aperture of an internal combustion engine and by which fouled, or practically inactive spark plugs in which the electrodes are encrusted with carbon deposits are subjected to 40 high temperatures and pressures effective to remove the carbon accumulations. The attachment receives the normal spark plug which is connected in the usual ignition circuit for controlling the normal operation of the engine and 45 in addition, the attachment also receives fouled spark plugs which are substantially inactive and which must be subject to cleaning operation.

My invention has several forms, all of which are attachable to internal combustion engines for 50 cleaning spark plugs during the normal operation of the engines, such as, for example, while an automobile is in normal use. The attachment is shaped to receive one or a multiplicity of spark plugs of fouled spark plugs to be cleaned.

55 Referring to the drawing in detail, reference

character 1 designates an internal combustion engine including the usual distributor 2, from which cables 3, 4, 5, and 6 lead to spark plugs 7, 8, 9 and 10, respectively. The engine, in the arrangement shown operates in the usual manner in which the spark plugs 7, 8, 9 and 10 are sequentially activated. The spark plug 8, however, is not mounted in the spark plug aperture 11 of the head 12 of the engine as is customary, and as is the case with the spark plugs 7, 9, and 10. In lieu of the direct mounting of spark plug 8 in the engine cylinder head 12, I provide mounting means for the spark plug 8 in the form of an adapter, or housing adaptable to the spark plug aperture 11 of engine cylinder head 12 as represented at 14 in Figs. 1, 2 and 3.

The adapter housing 14 includes an external screw-threaded terminus represented at 15, which is formed to engage the internal screw-threads 16 of the spark plug aperture 11 in the cylinder head 12. The adapter housing 14 has an internally screw-threaded vertical sleeve-like extension 17 on the upper end thereof for receiving the screw-threaded portion of the spark plug 8. Spark plug 8 is provided with electrodes 18, which connect in the distributor circuit through cable 4 for controlling the ignition in the engine cylinder directly beneath the cylinder head 12, with which the adapter housing is associated. Under these circumstances, the actual combustion chamber extends from the engine cylinder through the central portion 19 of the adapter housing 14 so that the ignition effected at electrodes 18 results in explosion at high temperature and pressure which permeates the entire area through the hollow central interior 19 of the adapter housing 14. Within this area of intensely high pressure at extremely high temperature of burning gases, I arrange the electrodes of the fouled, or substantially inactive spark plugs designated at 20, 21, 22 and 23. The fouled, or substantially inactive spark plugs 20, 21, 22 and 23 have their screw-threaded portions engageable with internally screw-threaded sleeve-like extensions 24, 25, 26 and 27 of the adapter housing 14. These internally screw-threaded sleeve-like extensions 24, 25, 26 and 27 of the adapter housing are relatively short for positioning the electrodes 28, 29, 30 and 31 of the fouled, or substantially inactive spark plugs 20, 21, 22 and 23, respectively within the area of high pressure and intensely high temperature in the hollow interior 19 of the adapter housing 14. The accumulation of carbon deposits on electrodes 28, 29, 30 and 31 have been represented at 28a, 29a, 30a and 31a, respectively. These hardened accumulations are subjected to the high pressure and extremely high temperatures which occur in the combustion chamber in the hollow interior 19 of the adapter housing 14 for disintegrating the accumulated deposits and cleaning the fouled, or substantially inactive spark plugs.

In lieu of the adapter housing for mounting four spark plugs as illustrated in Figs. 1-3, I may provide adapter housings which will support one, two, three or more fouled, or substantially inactive spark plugs in association with the active spark plug.

In Fig. 4 I have represented an adapter housing arranged to receive a single fouled, or inactive spark plug 32. In this arrangement the adapter housing is illustrated at 33 in the form of a Y, having an externally screw-threaded terminus 34 arranged to engage the internal screw threads 16 in the spark plug aperture 11 of the

cylinder immediately below cylinder head 12. The adapter housing 33 has sleeve-like extensions projecting on axes at substantially 60°, one sleeve-like extension being shown at 34, which is internally screw-threaded at 35 to receive the screw-threaded portion of the active spark plug 8, and the other sleeve-like extension, one of which is shown at 36, internally screw-threaded at 37 for receiving the screw-threaded portion of the fouled, or substantially inactive spark plug 32. The fouled, or substantially inactive spark plug 32 is shown as having electrodes 38 bearing an accumulation of encrusted carbon deposit 38a.

The electrodes 18 of spark plug 8 are activated through the ignition circuit of the internal combustion engine, producing combustion of the explosive mixture which fills the hollow interior of the substantially Y shaped chamber 39 of the adapter housing 33, thus producing high pressures and extremely high temperatures which serve to disintegrate the accumulated carbon deposits 38a of the fouled, or substantially inactive spark plug 32.

One of the principal advantages of the spark plug cleaner of my invention resides in the fact that fouled, or substantially inactive spark plugs may be cleaned without loss of time while an automobile is in actual operation and use. After a cleaning treatment of a relatively short time period, the accumulated carbon deposits on the electrodes of the fouled, or substantially inactive spark plugs are disintegrated, and the plugs are ready to be restored to normal service. Thus, one automobile may be used as a rejuvenator, or cleaning agency for unserviceable spark plugs and serve a large number of customers.

I have described my invention in certain preferred embodiments, but I realize that various modifications may be made, and I intend no limitations upon my invention other than may be imposed by the scope of the appended claims.

What I claim and desire to secure by Letters Patent of the United States is as follows:

1. A spark plug cleaner comprising an adapter housing externally screw-threaded to enter the spark plug aperture of an engine cylinder, an internally screw-threaded sleeve-like extension on said housing arranged to receive an activated spark plug for effecting combustion within said housing and a multiplicity of sleeve-like projections on said housing, each internally screw-threaded to receive fouled spark plugs having carbonaceous deposits on the electrodes thereof for treating the electrodes of said fouled spark plugs to the effects of high temperature and pressure within the region of said activated spark plug.

2. A spark plug cleaner comprising an adapter housing externally screw-threaded to enter the spark plug aperture of an engine cylinder, an internally screw-threaded sleeve-like extension on said housing, arranged to receive an activated spark plug for effecting combustion within said housing and plurality of radially extending sleeve-like projections on said housing, each internally screw-threaded to receive fouled spark plugs having carbonaceous deposits on the electrodes thereof for maintaining said electrodes within the region of high temperature and pressure immediately adjacent the activated spark plug.

3. A spark plug cleaner comprising an adapter housing externally screw-threaded to enter the spark plug aperture of an engine cylinder, an internally screw-threaded sleeve-like extension on

said housing arranged to receive an activated spark plug for effecting combustion within said housing and a multiplicity of angularly distributed sleeve-like projections integrally related to said housing, each of said sleeve-like projections being internally screw-threaded to receive the screw-threaded ends of fouled spark plugs having carbonaceous deposits on the electrodes thereof for maintaining the said electrodes within the region of combustion immediately adjacent said activated spark plug.

4. A spark plug cleaner comprising an adapter housing externally screw-threaded to enter the spark plug aperture of an engine cylinder, an internally screw-threaded sleeve-like extension on said housing arranged to receive an activated spark plug for effecting combustion within said housing, a pair of sleeve-like projections extending in diametrically opposite directions from said housing, each of said projections being internally screw-threaded for receiving the screw-threaded ends of fouled spark plugs having carbonaceous electrodes thereof for positioning said electrodes within a region of high pressure and high temperature immediately adjacent said activated spark plug for disintegrating the carbonaceous deposits on the said electrodes.

5. A spark plug cleaner comprising a Y shaped

adapter housing in which one terminus thereof is externally screw-threaded to engage the screw-threaded spark plug aperture of an engine cylinder, and in which the other terminal thereof are internally screw-threaded for receiving an activated spark plug and a fouled spark plug wherein said activated spark plug effects combustion within the said adapter housing and wherein the fouled spark plug is subjected to heat and pressure of the combustion within said housing.

6. A spark plug cleaner comprising an adapter housing of Y contour including a sleeve-like stem portion and a pair of V shaped sleeve-like portions, said stem portion being externally screw-threaded at the end thereof for engaging the screw-threaded spark plug aperture of an engine cylinder, and said V shaped sleeve-like portions, each being internally screw-threaded for receiving in one of said portions an activated spark plug for effecting a combustion within said housing, and receiving in the other of said portions a fouled spark plug having carbonaceous deposits on the electrodes thereof for subjecting said electrodes to high temperature and pressure within the region of said activated spark plug for disintegrating the said carbonaceous deposits on said electrodes.
